UNITED STATES PATENT OFFICE.

JAMES DRUMMOND SCHOFIELD AND CHARLES T. RAY, OF DALLAS, TEXAS, ASSIGNEES TO
THE TEXAS IMPLEMENT AND MACHINE COMPANY, A CORPORATION.

PLANTER.

No. 872,461.

Specification of Letters Patent.

Patented Dec. 3, 1907.

Application filed March 8, 1907. Serial No. 361,371.

To all whom it may concern:

Be it known that we, JAMES DRUMMOND SCHOFIELD and CHARLES T. RAY, citizens of the United States of America, residing at 5 Dallas, in the county of Dallas and State of Texas, have invented certain Improvements in Planters, of which the following is a specification.

Our invention is an improvement in riding 10 planters, and relates more especially to the provision of an improved steering device for the purpose of keeping the planter running in a straight line during the operation of the burster or furrow opener.

15 Our invention or improved steering device is particularly applicable to the class of single row riding planters or riding middle bursters, which are provided with means for bursting out old cotton stalks and rebedding. In the 20 operation of riding planters of this character considerable difficulty is experienced in keeping the bursters or sweeps on the ridge when they are cutting the cotton stalks, and in order to overcome the tendency of the 25 machine to shift laterally during this cutting operation various devices have been provided, such as rigid colters and knife-rudders, cross-head clevis adjustments, etc., but so far as we are aware none of these 30 devices have been found sufficiently effective or entirely satisfactory when the planter is cutting through heavy stalks.

Our invention therefore contemplates the provision of a steering device or colter 35 which can be deflected or shifted laterally so as to quickly check any tendency of the burster or sweep to move off the ridge. This is accomplished, as will be hereinafter seen, by swiveling the colter in a supporting 40 frame or bracket and providing means for operating the swivel-connection; all as will be fully described in the following specification.

In the accompanying drawings which form 45 a part hereof:—Figure 1 is a longitudinal side elevation showing the application of our invention to that style of riding planter which forms the subject-matter of the prior patent granted to J. D. Schofield Decem- 50 ber 20th, 1904, No. 777,754. Fig. 2 is an enlarged detail perspective view of our improved steering device. Fig. 3 is a de-

tail showing a modification hereinafter referred to.

Like numerals of reference indicate like 55 parts in all the figures of the drawings.

In carrying out our invention we provide a supporting frame or bracket 1, which may be of any approved form of construction, but in the present instance, and as shown, 60 comprises an attaching plate 2 and integral bearing arms 3 3, the latter being spaced apart and provided with vertical openings which are adapted to receive and form the 65 bearings for a vertical shaft or standard, as 4.

The vertical shaft or standard 4 carries at its lower end a revolving colter 5, and at its upper end is provided with a cross-bar 6, which is shaped at its ends to form stirrups 70 7, said cross-bar constituting the means by which the shaft or standard is turned in its bearings. The cross-bar is preferably connected detachably to the shaft or standard, and for this purpose is provided centrally 75 with a sleeve 8 to receive the shaft or standard, and with a binding-screw 9 which is threaded through the sleeve and impinges against said shaft or standard.

Interposed between the upper bearing 3 80 of the supporting bracket and a collar 10 adjustably mounted on the shaft or standard below said bearing is a compression spring 11, which is adapted to exert a yielding pressure on the standard and therefore permit 85 the colter to ride over a stone or other obstruction and prevent any injury to said colter.

Instead of employing a colter, as shown in 90 Figs. 1 and 2 of the drawings, we may, in some instances use what is commonly known 95 as a knife-rudder, as illustrated in Fig. 3. In adapting the device to this style of rudder, the lower end of the shaft or standard, as 12, is bent rearward and flattened to provide a vertically disposed trailing blade 13. In this instance the shaft or standard 12 is adapted to fit the bearings 3 of the supporting bracket 1, so that the knife-rudder and its standard may be used in connection with 100 such bracket.

In Fig. 1 of the drawings we have shown the application of our invention, and in that instance the supporting bracket 1 which car-

ries the steering blade or colter is attached to the standard of the forward or main shovel of the planter and so that the colter or blade will follow and operate in the rear of the 5 same. It is obvious, however, that the device may be attached to any other part of the planter, but when it is adapted to be operated by the feet of the driver it should be located with respect to the seat that the feet 10 of the driver may conveniently rest within the stirrups.

The device operates similar to the ordinary rigid colter or knife-rudder, with the exception that by means of the swivel connection 15 the colter or knife-rudder in the present instance may be shifted or deflected after the manner of a ship's rudder and thereby quickly bring the burster or shovel or cutter back to the ridge so as to keep it in a straight line 20 therewith.

As herein shown and described the shifting of the colter or knife-rudder is effected by pressure of the driver's feet upon the ends of the cross-bar, but it is apparent that other 25 means for operating the swiveled standard may be provided, such for instance as the ordinary hand-lever and suitable connections.

Having thus described our invention, what 30 we claim as new and desire to secure by Letters-Patent, is:—

1. In a riding planter, the combination with a support, of a vertical standard vertically movable and rotatable in the support, a 35 rudder-blade at the lower end of the standard, stops for limiting the vertical movement

of the standard, means for yieldingly supporting the standard in its support, and means for turning said standard.

2. The combination, in a planter, of a 40 steering device therefor comprising a rotatable standard, a rudder-blade at the lower end of said standard, a compression spring acting on the standard, and means for turning the standard.

3. The combination, in a riding planter, of a steering device therefor comprising a supporting bracket, a standard rotatable therein, a rudder-blade at the lower end of said standard, an adjustable collar on the standard, 50 a compression spring interposed between the collar and bracket, and means for turning the standard.

4. The combination, in a riding planter, of a steering device therefor comprising a supporting bracket, a standard rotatable therein, a rudder-blade at the lower end of said standard, a collar adjustable on the standard, a compression spring interposed between the collar and bracket, and a cross-bar 55 secured to the upper end of the standard and provided with stirrups at its ends, substantially as herein shown and described.

In testimony whereof we have signed our names to this specification in the presence of 60 two subscribing witnesses.

JAMES DRUMMOND SCHOFIELD.
